UNITED STATES PATENT OFFICE.

WILLIS S. GIBBONS, OF RUSSELL, NEW YORK.

SPRING-CLASP.

SPECIFICATION forming part of Letters Patent No. 439,652, dated November 4, 1890.

Application filed April 17, 1890. Serial No. 348,308. (No model.)

To all whom it may concern:

Be it known that I, WILLIS S. GIBBONS, of Russell, in the county of St. Lawrence and State of New York, have invented a new and useful Improvement in Spring-Clasps, of which the following is a specification, reference being had to the accompanying drawings forming part thereof.

My invention relates to that class of spring-clasps, principally designed for use on overshoes, composed of two members, the one comprising a base plate or plates having pivotally mounted thereon a spring-actuated tongue, and the other consisting of a transversely-slotted plate adapted to operatively engage said tongue, each of said members being provided with means whereby it can be secured to the instep-flap of an overshoe, or to any article upon which the clasp is adapted to be used. In such clasps, as heretofore constructed, the tongue has been provided with two laterally-projecting ears or lugs, which, by projecting between two plates of spring metal superposed one upon the other and forming the base, constitute the pivot or hinge upon which the tongue turns, the action of said plates upon said ears or lugs being relied upon to retain the tongue in both its open and closed positions. The tongue is thus mounted upon the base at one end of the latter, and is of such length that in its closed position its free end projects considerably beyond the base, and rests upon the strap or other device to which the base is secured. The clasp thus constructed has been found to be open to serious objections, some of which are as follows: The ears or lugs which form the pivot of the tongue are frequently bent or broken in the use of the clasp, and when this occurs the clasp is rendered worthless, as the cost of renewing said ears or lugs usually exceeds the original cost of the clasp. The slight leverage of the plates composing the base upon the tongue renders the spring-action of the former insufficient to properly retain the tongue in its closed position, and as a consequence the strain on the clasp frequently moves the tongue to its open position, thereby releasing the slotted plate comprising the second member of the clasp, from its engagement with said tongue. Again, the free end of the tongue, by projecting beyond

the base in the closed position of said tongue, is exposed in such manner that objects with which the clasp is brought into contact are liable to force the tongue to its open position, as well as to bend or break it, and this liability is increased by the fact that the connection between the base and its strap or other device is overlapped by the tongue in its closed position, thereby causing the free end of the tongue to stand out somewhat from said strap.

It is the object of my invention to provide a clasp which will be free from the defects above noted, and which will be much stronger and more durable than those heretofore constructed.

To these ends my invention consists in the clasp constructed and operating as hereinafter fully described, and particularly pointed out in the claims.

Referring to the drawings, in which like letters designate like parts in the several figures, Figure 1 is an isometric view of the clasp with the two members thereof in operative engagement with each other. Figs. 2 and 3 are similar views of the two members of the clasp separated from each other. Fig. 4 is a longitudinal sectional view of the clasp, as shown in Fig. 1.

The letter *a* designates a transversely-slotted plate, forming one member of the clasp, which plate is or may be similar in its construction to those heretofore employed. The second member of the clasp is composed of a base *b* and a tongue *c*, pivotally mounted thereon. We prefer to make said base of a single plate of steel or other suitable metal, having a centrally-located open recess at one end thereof to receive the rear end of the tongue. At the ends of the two portions of the plate lying upon opposite sides of said recess are located eyes *b'*, through which and corresponding eyes *c'* on the tongue extends a pin *b*², which forms the pivot upon which the tongue turns from its open to its closed position, and vice versa. The eyes *b'* *c'* will, preferably, be formed integrally with the base and tongue, respectively, by bending up portions thereof or otherwise; but can be soldered or otherwise secured thereto, if desired. A very strong and durable connection between the tongue and base is thus formed, and should the pin

b^2 be bent or broken it can be readily removed and straightened or a new one inserted without disturbing the other parts of the clasp.

The letter d designates a flat spring, which is riveted or otherwise secured to the base at one end, and at its opposite end bears against a lug or lip c^2 on tongue c in such manner as to normally retain the tongue in either its open or closed position. As herein shown, said lip or lug c^2 is formed by bending the end of the tongue to the proper shape beyond the plane of the eyes c' , (see Figs. 3 and 4); but it can be otherwise formed, and can be secured to the tongue in any suitable manner. The length of said lug is such as to afford the spring sufficient leverage upon the tongue to prevent accidental movement of the latter in the use of the clasp, and a common cause of objection to such clasps as heretofore made is obviated. The relative lengths of the base and tongue are such that the former projects beyond the end of the latter when it is in its closed position, as shown in Figs. 1 and 4, and in such projecting portion of the base is made the opening b^3 to receive the strap or other device to which it is secured, and I prefer to make said opening of such size that the free end of the tongue will overlie a portion thereof in the closed position of the tongue to facilitate inserting the finger beneath the tongue to move it to its open position, said free end of the latter being preferably made slightly concavo-convex in cross-section for the same purpose, as shown in Fig. 3. By thus locating the strap-opening beyond the end of the tongue the latter is permitted to closely hug the base when in its closed position, and the possibility of accidental movement thereof is rendered very remote. To still further guard against such accidental movement of the tongue, however, I provide the base with flanges b^4 at the sides thereof, which flanges may be formed integral therewith or secured thereto. The outer edge of said flanges projects beyond the plane of the outer side of the tongue in the closed position of the latter, and is preferably curved to correspond with the curvature of said tongue, as shown. When the tongue is in its closed position, said flanges form solid walls extending from end to end thereof to prevent any object from entering between the tongue and base to move the former away from the latter.

As hereinbefore stated, the clasp thus constructed is especially designed for use upon overshoes, and in such case the two members thereof will be curved longitudinally, as shown, and will be secured to the instep-flaps of the shoe, as represented in Fig. 1, or in any suitable manner. The two members of the clasp are engaged with and disengaged from each other in the usual manner. Overshoes provided with clasps are much worn by lumbermen and others engaged in heavy out-of-door work, and much trouble and annoyance has been caused by the fact that in walking

through deep snow and among logs and underbrush, the tongue is constantly being forced from its closed to its open position, thereby permitting the two members to separate from each other and loosening the shoe. In the clasp devised by me the powerful action upon the tongue by its spring, the relative lengths of the tongue and base, and the guards at the sides of said base entirely obviate such objection, as the tongue cannot be accidentally moved from its closed to its open position.

The clasp herein shown and described can be manufactured at a slight cost by stamping its parts from sheet-steel or other suitable metal, and then bending said parts to the desired form, and it is obvious that modifications in the form of the several parts as well as in the various details of construction can be made without departure from the spirit of my invention. For example, it is obvious that the application of the guards devised by me to the sides of the base in the form of clasp heretofore used, would to a great extent obviate the objections to which it is now open, while such a construction would be manifestly included within the scope of my invention. It is obvious, furthermore, that the particular construction of the tongue-supporting member of the clasp, as herein set forth, is not dependent upon the particular construction of the second member or the one which engages the tongue, and that the form of the latter can be changed, as may be desired, without affecting the former.

Having thus fully described my invention, what I claim, and desire to secure by Letters Patent, is—

1. In a clasp of the kind described, a tongue-supporting member composed of a base-plate having an opening therein near one end thereof, said plate having a tongue pivotally secured to said plate at the opposite end of the latter, said tongue being of such length that in its closed position its free end will register with the opening in said plate and having said free end curved transversely to facilitate the insertion of the finger thereunder, and a second member composed of a slotted plate adapted to operatively engage said tongue, combined and operating substantially as and for the purpose described.

2. In a clasp of the kind described, a tongue-supporting member composed of a base-plate having pivotally connected thereto at or near one end thereof a tongue and having projections extending from the face thereof at substantially a right angle to said face to a point beyond the plane occupied by the tongue in its closed position, whereby said projections are adapted to serve as guards to said tongue, and a second member composed of a slotted plate adapted to operatively engage said tongue, combined and operating substantially as set forth.

3. The clasp herein described composed of two members, one of said members consisting

of a longitudinally-curved base-plate having pivotally connected to one end thereof a spring-actuated tongue which is of less length than said plate and having at the two sides thereof outwardly-extending flanges, which project to or beyond the plane occupied by said tongue when in its closed position, and the other of said members consisting of a longitudinally-curved plate having therein a se-

ries of transverse openings to receive said tongue, each of said members being provided with means whereby they can be secured to the instep-flaps of an overshoe, substantially as and for the purpose set forth.
